UNITED STATES PATENT OFFICE

CLARENCE J. WEBER AND ROY A. SEEK, OF CHICAGO, ILLINOIS, ASSIGNEES TO NATIONAL BRICK COMPANY, OF CHICAGO, ILLINOIS, A CORPORATION OF ILLINOIS

HOIST

Original application filed June 29, 1926, Serial No. 119,312. Divided and this application filed April 18, 1927. Serial No. 184,468.

Our invention pertains in general to trucks or trailers and more particularly to hoisting mechanism therefor of the same general character as that disclosed in our co-pending application, Serial No. 119,312, filed June 29, 5 1926, of which the present application is divisional.

In accordance with the general features of our invention there is provided a hoist cylinder having a pivotal mounting and resilient 10 means associated with the mounting comprising a plurality of leaf springs adapted to at all times urge the cylinder into a true vertical position with respect to the chassis of the truck.

15 In accordance with other features of our invention, we have provided novel detachable connections between the hoist cylinder and the source of hydraulic power, which connections permit of the cylinder being disconnected with facility from the hydraulic power unit.

20 In accordance with still other features of our invention, we provide in the connections between the hoist and the pump a three way 25 valve construction for controlling the operation of the hoist. This valve permits of a vibratory movement being imparted to the hoist plunger to cause the same to jar the 30 trailer body and thus cause all of the contents thereof to be quickly discharged. Then, too, the valve may be actuated to disconnect the pump from the hoist cylinder and to thus cause the plunger to be maintained in a given 35 stationary position or to cause all of the fluid to be discharged into the tank to lower the hoist plunger depending upon the position of the valve control member.

Also, we have from experience found that 40 the cup leather associated with the hoist piston tends to wear out much faster than is usual, due to the fact that it is flexed considerably. We have remedied this condition by positioning the cup leather in a substantially central position with respect to the pis-

ton, and by providing the piston with piston rings on each side of the cup leather. These piston rings serve to confine the cup leather and also to relieve the cup leather of considerable wear by preventing it from being flexed 50 to any considerable extent.

Other objects and advantages of our invention will more fully appear from the following detailed description taken in connection with the accompanying drawings which illustrate one embodiment thereof and in which,

55 Fig. 1 is a side elevation of a truck and trailer having associated therewith a hoisting device embodying the features of our invention;

60 Fig. 2 is an enlarged view of the hoist cylinder and its pivotal mounting;

65 Fig. 3 is a sectional view taken on the line 3-3 of Fig. 2 looking in the direction indicated by the arrows;

Fig. 4 is a sectional view of our novel hoist 70 piston construction; and

Fig. 5 is an enlarged sectional view of the three-way control valve associated with the pumping mechanism and oil tank.

75 Referring now to the drawings in detail, in which like reference numerals designate similar parts throughout the several views, 10 denotes generally a tractor (Fig. 1) which may be of any conventional construction. The tractor 10 is provided with the usual turn table 11 to which one end of a trailer 12 is connected. The tractor 10 and the trailer 12 comprise a truck, such as is well known in the automotive art. The trailer 12 is equipped with the customary body 13 having one end pivotally attached at 14 to the rear of the trailer 12. The front end of the body 13 is adapted to be raised to a position such as that 80 illustrated by dotted lines in Fig. 1.

85 The body 13 is adapted to normally rest upon the frame 15 of the trailer 12. The rear end of the frame 15 is provided with a pair of wheels 16 and a pair of springs 17. The front end of the frame 15 is adapted to rest 90

upon the turn table 11 associated with the chassis 18 of the tractor 10. Normally, the front end of the frame 15 will be connected to the said turn table 11.

5 The frame 18 of the tractor 10 carries a pair of gas tanks 19 and 20 which supply the fuel to the power unit of the tractor 10. These gasoline tanks 19 and 20 are positioned immediately behind the driver's station 21.

10 Mounted upon the front end of the trailer frame 15 is a hoisting device designated generally by the reference character 25. This device is adapted to be utilized to raise the body 13 about its pivot to a position such as that illustrated by dotted lines in Fig. 1. The device 25 includes a vertical cylinder 26 and a reciprocable plunger 27 mounted within the cylinder 26. The plunger 27 is preferably tubular in construction and has associated 20 with its lower end a piston 28.

The piston 28 (Fig. 4) comprises a pair of annular members 29 and 30 separated by a cup leather 31. The annular member 29 is equipped with a reduced portion 32 which telescopically telescopes the lower end of the tubular plunger 27. The reduced portion 32 may be fastened to the plunger 27 in any desirable manner. The annular member 29 is also provided with an annular stud 33 which extends 30 through an aperture 34 in the center of the cup leather 31 and through an aperture 35 in the center of the annular member 30. The annular member 30 is preferably equipped with an annular recess 36 in which a nut 37 is threaded upon the exposed end of the stud 33. This nut 37 serves to draw the members 29 and 30 together and serves to fasten the members and cup leather rigidly together. The annular member 30 is provided with a 40 reduced portion 38 between the periphery of which and the inner wall of the cylinder 26 is located the annular rim 39 of the cup leather 31. In other words, the annular member 30 in reality telescopes the cup leather 31 and thus tends to prevent undue flexing of the cup leather. The annular member 29 is provided with a piston ring 40 and the annular member 30 is provided with a piston ring 41.

50 The piston rings 40 and 41 engage the inner periphery of the cylinder 26 and serve to relieve the cup leather 31 of some of the strains and stresses imposed thereon when the plunger 27 is actuated. Since the cup leather 31 is confined intermediate the telescoping annular member 30 and the inner wall of the cylinder 26 it cannot flex as freely as in prior piston constructions. This arrangement increases the longevity of the cup leather and insures a reliable service on the 60 part of the piston 28. Heretofore, the cup leather was caused to be flexed considerably upon the reversal of the direction of movement of the plunger in the cylinder. In our construction the cup leather 31 cannot thus flex upon the reversal of the movement of the

plunger due to its being confined intermediate the two members 29 and 30.

65 The upper end of the plunger 27 has fastened thereto a cross arm construction 45 which carries a pair of revolvable pulleys 46. Each pulley 46 is pivotally attached to an arm 47 pivotally bolted to the cross arm construction 45.

70 Referring now to Fig. 3, the upper end of the cylinder 26 is preferably threaded and provided with a cap 50 threaded thereon. The cap 50 has a plurality of notches 51 preferably four in number for enabling the same to be turned with facility. The plunger 27 extends through an aperture 52 in the cap 51. The aperture 52 is preferably countersunk as indicated at 53, in order to accommodate a gland member 54 threaded into the upper part of the cap 50. The gland member 54 is provided with a central aperture 55 through which the plunger 27 extends.

75 The lower part of the cylinder 26 is tightly fitted in a pivotally mounted member 56. This member 56 is provided with a pair of diametrically opposed extensions 57 and 58 journaled in bearing brackets 59 and 60. Thus it will be seen that the lower end of the plunger cylinder 26 is pivotally mounted. The bearing brackets 59 and 60 are secured to portions 62 and 63 of a base plate 64 by means of bolts 65. The portions 62 and 63 are elevated from the plane of the base plate 64. The base plate 64 is provided with a pair of flanges 66 and 67 bolted to the channel irons 68 and 69 of the frame 15. The base plate 64 is also equipped with a pair of raised portions 71 and 72, upon each of which portions is supported a spring construction designated generally by the reference character 70. Since both of the spring constructions are identical, it is believed the description of one will suffice for both.

80 The spring construction 70 comprises a plurality of leaf springs 74 which vary in length. The springs 74 are held together by means of the usual clip 75. The longest leaf spring 74 abuts the outer wall of the cylinder 26, as indicated at 76. The lower ends of the leaf springs 74 abut the top of the raised portion associated therewith. The springs are 85 bolted to a lateral extension 78 projecting upwardly from the base plate 64. A clamping plate 79 and a plurality of bolts and nuts 80 are preferably employed for clamping the spring to the lateral extension 78.

90 Now it will be obvious that the spring construction 70 will normally function to maintain the hoist cylinder 26 in a vertical position with respect to the base plate 64. However, upon the raising of the body 13 by the plunger 27, the cylinder 26 will begin to tilt about its pivot towards the rear of the trailer 12. This movement will be resisted by the spring construction 70 nearest to the body 13. The degree to which the cylinder 95

26 will pivot about the axis of its pivotal mounting will depend upon the load in the body 13. That is to say, the tilting will be proportional to the weight of the load in the truck body 13.

5 Each pulley 46 has passing over its groove a cable 80, one end of which is fastened to a channel beam 81 of the body 13 and the other end of which is fastened to an eyelet 82 secured to the base plate 64. The pair of cables 80 are utilized upon the raising of the pulleys 46 by the plunger 27 to raise the associated end of the body 13.

Associated with the cylinder 26 intermediate its ends is a ring of metallic material 90. This ring may be secured to the outer wall of the casing or cylinder 26 by any suitable means. This ring 90 constitutes a support for the flexible connections to be hereinafter described. Fastened to this band 90 is a tubular block 91 (Fig. 2) into which one end of a rigid pipe line 92 discharges. The other end of the pipe line 92 is connected to an outlet in the cylinder wall 26, designated by the reference character 93. The pipe line 92 may be provided with a union 94 intermediate its ends to facilitate the disconnecting of the pipe line from the cylinder 26 whenever it is desired. Also secured to the 25 ring 90 is a tubular block 91' which is identical in construction to the block 91. Connected to this block 91' is a pipe line 95, the lower end of which communicates with an inlet 96 for the cylinder 26. The pipe line 95 is also 30 equipped with a union 97 positioned intermediate its ends. Since both the blocks 91 and 91' are identical in construction, it is believed a description of one will suffice for both. Each block 91 is provided with a lateral projection 98 having a tapered orifice portion 99. The projection 98 is tubular in construction and communicates with the pipe line associated with the block.

Associated with the projections 98 of the blocks 91 and 91' are a pair of flexible lines 45 100 and 101. The line 100 constitutes the inlet lead for the hoisting device and the line 101 constitutes the outlet for the hoisting device. Each of these lines has an end provided with a metallic ring of material 102 to which is pivotally attached a yoke member 103 for straddling the associated projection 98. The yoke member 103 has an adjustable screw 104 adapted to be moved into engagement with the top of the corresponding projection 98. The tapered portion 99 of the projection is adapted to be inserted into the end of the pipe line and the pipe line is adapted to be tightly held in place on the projection 55 by means of the yoke and the associated screw 104.

It should of course be understood that the inlet pipe line 100 is associated with the block 91' communicating with the inlet pipe 60 95 and that the pipe line 101 is associated

with the block 91 communicating with the outlet 93. The detachable connections, including the yoke members 103 previously described, enable the pipe lines 100 and 101 to be detached from the hoist cylinder 26 with facility. This is particularly advantageous 70 when it is desired to disconnect the trailer from the tractor.

Referring now to Fig. 1, it will be observed that the inlet pipe line 100 communicates with a three-way valve 105. The flexible pipe connection 101 has its other end connected to a pipe 106 discharging into an oil tank 107. The upper end of the pipe 106 communicates with the three-way valve 105. The three-way valve is also connected by a flexible connection 107' to a pumping mechanism, designated generally by the reference numeral 108. The pumping mechanism is connected by a pipe line 109 to the bottom of the oil tank 107. The oil tank 107 and the pumping mechanism 108 are preferably disposed intermediate the two gas tanks 19 and 20, previously described.

We have illustrated somewhat diagrammatically in Fig. 5 a three-way valve construction 105 for controlling the operation of our hoist. The valve proper includes a T body 111, a valve member 112 and a handle 110 connected to the valve member 112 for actuating the same. The valve member 112 is adapted to be utilized to close any one of the three ports of the valve. Port 113 communicates with the pipe line 100, port 114 communicates to the oil tank 107 through the pipe line 106, and port 115 communicates to the pump mechanism 108 through the pipe line 107.

It will be obvious from Fig. 5 that when the valve member 112 is in the position illustrated, the pump will be forcing fluid or oil to the hoisting cylinder 26. After the plunger 27 has been moved to its uppermost position, the oil entering the cylinder 26 from the pump will cause the plunger 27 to vibrate. This vibratory movement on the part of the plunger 27 jars the body 13 and enables all of the contents to be discharged therefrom quickly. Now, by operating the handle 110 to cause the valve member 112 to close the port 115, 115 the pumping mechanism 108 will be disconnected from the three-way valve 105. This will result in the plunger 27 forcing the oil out of the cylinder 26 through the pipe line 95, through 100, port 113, into the port 114 120 and into the tank 107. In other words, when the port 115 is closed, the plunger 27 will be moved to its lowermost position.

On the other hand, when the port 113 is closed, the plunger 27 will not oscillate, but, on the contrary, will remain at a given raised position. The oil pumped through the line 107' by the pump 108 will be by-passed by the valve 105 into the tank 107. Thus it will be seen that through the three-way valve 105 130

liquid may be either pumped to the hoist, bypassed to the tank, or the oil in the cylinder 26 may be caused to be discharged into the tank 107 by the hoist plunger 27.

5 We desire it understood that although we have described in detail the preferred embodiment of our invention, the invention is not to be limited thereby, but only in so far as defined by the scope and spirit of the appended claims.

10 We claim:—

1. In combination, in a hoisting device, a hoist cylinder, a reciprocable plunger in the said cylinder, a fluid tank associated with the 15 said cylinder, a pump for pumping fluid from the tank to the cylinder to raise the plunger therein, a pipe line between the said pump and the lower part of the cylinder, a pipe line for an overflow between the upper part of the 20 cylinder and the tank, a pipe connection between the said pipe lines, the pipe line between the pump and the lower part of the cylinder being adapted to supply fluid for operating the plunger independently of the pipe line 25 from the top of the cylinder, and a control valve associated with the said connection for controlling the raising and lowering of the plunger within the cylinder, said valve when in one position serving to cause the fluid coming from the pump to vibrate the said plunger, and when in another position serving to cause the plunger to be maintained stationary in a given elevated position.

2. In combination, in a hoisting device, 30 a hoist cylinder, a reciprocable plunger in the said cylinder, a fluid tank associated with the said cylinder, a pump for pumping fluid from the tank to the cylinder to raise the plunger therein, a pipe line between the said pump and the lower part of the cylinder, a pipe line for an overflow between the upper part of the cylinder and the tank, a control valve, a pipe connection between the said pipe lines, control valve and tank, the pipe line between the 40 pump and the lower part of the cylinder being adapted to supply fluid for operating the plunger independently of the pipe line from the top of the cylinder, said valve being adapted for regulating the raising and lowering 45 of the plunger within said hoist cylinder.

3. In a hoisting device, a hoist cylinder, a plunger operable therein, a fluid tank, a control valve, a pump, a pipe line delivering from the pump to said valve, a pipe line delivering 55 from the valve to the bottom of the cylinder for raising said plunger, a pipe line for an overflow delivering from the top of the cylinder back to the tank independently of the fluid supply line from the pump to the bottom of the cylinder, a pipe line delivering from the valve to the tank, and a pipe line delivering from the tank to the pump, said valve being operable to selectively connect the pipe line delivering from the pump to the 60 valve with the pipe line delivering from the 65

valve to the hoist cylinder, the pipe line leading from the pump to the valve with the line delivering from the valve to the tank, or the line leading from the valve to the hoist cylinder with the line leading from the valve to the tank. 70

4. In combination, a hoist cylinder, a reciprocable plunger in said cylinder, a fluid tank associated with said cylinder, a pump for pumping fluid from the tank to the cylinder 75 to raise the plunger therein, a control valve, a pipe line from said pump through said valve to the lower part of the cylinder, a pipe line between said valve and tank, said valve controlling the raising and lowering of the 80 plunger within the cylinder, the valve when in one position cooperating with an overflow pipe line from the top of the cylinder to the tank causing the raised plunger to vibrate, and when in another position serving to maintain the plunger stationary in a predetermined elevated position. 85

In witness whereof, we hereunto subscribe our names this 12 day of April 1927.
